UNITED STATES PATENT OFFICE.

CHARLES J. KLEIN, OF NEW YORK, N. Y., ASSIGNOR TO THE GENERAL INCANDESCENT ARC LIGHT COMPANY, OF SAME PLACE.

ELECTRIC SWITCH.

SPECIFICATION forming part of Letters Patent No. 635,691, dated October 24, 1899.

Application filed February 24, 1899. Serial No. 706,674. (No model.)

To all whom it may concern:

Be it known that I, CHARLES J. KLEIN, a citizen of the United States, residing in the city of New York, borough of Manhattan, 5 county and State of New York, have invented certain new and useful Improvements in Electric Switches, of which the following is a specification.

My invention relates to electric switches 10 adapted to effect a rapid closure or break of the electric circuit.

I will describe electric switches embodying my invention and then point out and claim the novel features of my invention.

15 In the accompanying drawings I have illustrated several forms of switch, each embodying the central idea of my invention, although I do not wish to confine myself to switches shown, as the details may be varied without departing from the spirit of my invention.

20 In the drawings, Figure 1 is a plan view of a hand-snap switch embodying my invention. Fig. 2 is a side view thereof. Fig. 3 is a plan view of a single push-button switch embodying my invention, Fig. 4 being a sectional side elevation thereof on line 4 4 of Fig. 3. Fig. 5 is a sectional side elevation of a double push-button snap-switch embodying my invention. Fig. 6 is a bottom view of the switch 25 shown in Fig. 5. Fig. 7 is a top view thereof. Fig. 8 is a sectional side elevation showing the contacts, and Fig. 9 is a detail of the shoe.

In the drawings similar letters of reference refer to similar parts in all the figures.

30 Referring for the present to Figs. 1 and 2, *a* is a porcelain insulation-base for the support of the contacts. *b* are the contacts. *c* is the supporting frame or bar, having a bearing face or surface *c'*. *d* is a rocking lever, 35 shown in the present instance as pivoted at *d'* and provided with a bearing face or surface *d''*. The switching piece or bar *e* is preferably carried upon the end of a cross-bar *f* and preferably insulated therefrom. One of 40 these switching-pieces is carried at each end of the cross-bar, although but a single piece can be so carried, if desired. Carried upon the cross-bar *f* is a shoe *g*, which carries the switching piece or pieces *e* and slides upon 45 the bearing-face *c'* of the upright or supporting-frame *c*. *h* is a grooved roller which

bears upon the bearing-face *d''* of the rocking lever *d* and is provided with an axle *i*, to which a spring or springs *j* are secured, which spring or springs connect the roller-axle *i* with 55 the cross-bar *f*.

The operation of the switch will be apparent from the drawings. Upon rocking the lever *d*, let us say in the direction of the arrow, the bearing-surface *d''* becomes inclined 60 with respect to the bearing-surface *c'*, so that the tension of the spring or springs being exerted to pull the shoe and roller toward each other the said shoe and roller will be snapped downward, causing the contact-piece 65 *e* to close the circuit between the contacts or springs *b b*. The parts will then be in the position shown in dotted lines. When it is desired to open the switch, the lever *d* is rocked in the opposite direction, thereby increasing the tension on the springs *j* and inclining the upper end of the bearing-surface *d''* toward the bearing-surface *c'*, whereupon 70 the shoe and roller will rise, breaking the circuit.

75 It will be apparent that the underlying principle of my invention may be variously applied, and I have shown by way of example the principle applied to other forms of switches.

80 In Figs. 3 and 4 a single push-button is employed. In these figures, *k* is a spring-restored push-button, which operates upon a rocking lever *d*, acting upon a guide or supporting frame *c* in proximity to contact-springs *b*. 85 The supporting-frame *c* carries a sliding shoe or contact-piece *g*, which is connected by a spring *j*, whose end or moving piece moves on the rocking lever *d*.

In Figs. 5, 6, 7, and 8 a shoe *g* slides upon 90 a supporting-frame *c* and carries a shaft *f*, provided with contacts *e*, placed in operative proximity to circuit-terminals or contact-springs *b*. Pivoted to the frame *c* is a rocking lever *o*, provided with a bearing-surface 95 *d''* and stops *d''*. This rocking lever is operated by a pair of push-buttons *k k* and is provided with a roller *h*, connected to the shoe *g* by means of springs *j*. The switches shown in Figs. 3, 4, 5, 6, and 7 operate in a similar 100 manner to the switch shown in Figs. 1 and 2. The shaft *f* is insulated from the contact-

blocks *e* by insulation *l*. The shoe has a projection *l'* entering between the side bars of the supporting-frame *c*, as clearly seen in Fig. 9.

5 Having described my invention, what I claim, and desire to secure by Letters Patent, is—

1. In an electric snap-switch, the combination with circuit-terminals, of means for closing the circuit between the terminals comprising a plurality of bearing-surfaces one capable of being inclined with respect to the other, a plurality of moving pieces each freely moving or sliding upon a bearing-surface and 15 a spring connection between the moving pieces whereby an electric circuit may be opened or closed by inclining one of the bearing-surfaces with respect to the other, substantially as described and for the purposes 20 set forth.

2. In a switch of the character described, the combination with circuit-terminals, of means for closing the circuit between the terminals comprising a fixed bearing-surface, a 25 movable bearing-surface, a plurality of spring-connected pieces one bearing upon each of the bearing-surfaces whereby when the movable bearing-surface is inclined with respect to the other bearing-surface a movement of 30 opening or closing the switch is effected.

3. In an electric switch, the combination with circuit-terminals, of means for closing the circuit between the terminals comprising the supporting frame or bar *c*, the rocking 35 lever *d* and a plurality of moving pieces one moving freely upon the supporting frame or bar and the other moving freely upon the

rocking lever, and a spring connection between the two moving pieces, whereby upon movement of the rocking lever the spring 40 connection will be effective to open or close the switch.

4. In an electric switch, the combination with circuit-terminals, of means for closing the circuit between the terminals comprising 45 a supporting-frame and rocking lever provided with bearing-surfaces capable of being made substantially parallel with or being inclined with respect to each other and a plurality of freely-moving pieces one coöperating 50 with one bearing-surface and the other with the other bearing-surface and a spring connection connecting the said two moving pieces whereby when the bearing-surfaces are substantially parallel with each other the movable pieces will receive no motion and when the bearing-surfaces are inclined with respect to each other the moving pieces will be forced by their spring connection to move in the direction of the narrowest portion of the space 55 between the said two bearing-surfaces.

5. In a switch of the character described, the combination with circuit-terminals, of means for closing the circuit between the terminals comprising the upright *c*, the lever *d* 60 pivoted thereto, the shoe *g* and roller *h* and a spring connection forcing the shoe and roller toward each other whereby upon swinging the lever *d* the switch may be opened or closed.

CHARLES J. KLEIN.
